Primary Examiner — Jennifer Rivard(74) *Attorney, Agent, or Firm* — John M Lipchitz(57) **CLAIM**

The ornamental design for a shaving razor handle, as shown and described.

DESCRIPTION

FIG. 1 is a perspective view of a shaving razor handle showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is another perspective view thereof with unclaimed portions removed for clarity;

FIG. 9 is another front view thereof;

FIG. 10 is another rear view thereof;

FIG. 11 is another right side view thereof;

FIG. 12 is another left side view thereof;

FIG. 13 is another top view thereof; and,

FIG. 14 is another bottom view thereof.

The broken lines illustrate the environment for the shaving razor handle and form no part of the claimed design.
